VENETIAN BLIND TILT CONTROL MEANS

Michael L. Kesner, Chicago, Ill.

Application August 12, 1948, Serial No. 43,871

8 Claims. (Cl. 160—170)

1

This invention relates to improvements in Venetian blinds, and particularly to improvements in the tilt-operating means for the louvres of blinds suspended from a spring-actuated roller arranged for raising the blinds. This invention relates to and comprises improvements upon the construction shown and described in my copending application Serial No. 656,968 filed March 25, 1946, for Auto-tilt Venetian Blind, now patent 2,521,980 issued September 12, 1950.

The main objects of this invention are to provide an improved means for adjusting the angular setting of the louvres of a Venetian blind through the agency of the spring-powered roller by which the blind is operated; to provide an improved louvre-operating means in which the angular position, or tilt, of the louvres is determined by the position to which the blind is raised or lowered; to provide an improved louvre-tilt operating means wherein the turning or angular movement of the louvres is limited to less than a complete revolution regardless of the extent of turning of the actuating roller; to provide such an operating means arranged to automatically disengage the driving connection between the louvre tilting member and the actuating roller when the louvres reach a predetermined position of tilt; to provide an improved Venetian blind having louvres that are operated through up-and-down adjustment of the blind and in which the turning movement of the louvres is limited regardless of the extent of up-and-down adjustment of the blind; and to provide an improved automatic louvre operating means that will obviate flutter or back-and-forth oscillation of the louvres during the operation of raising and lowering the blind.

An illustrative embodiment of this invention is shown in the accompanying drawings in which

Figure 1 is a fragmentary, front-elevation view of a Venetian blind showing the improved louvre-operating means.

Fig. 2 is a sectional view as taken on line 2—2 of Fig. 1, showing the arrangement of the louvre-operating elements.

Fig. 3 is a sectional view as taken on line 3—3 of Fig. 2, showing the construction of the louvre-operating means and the arrangement for mounting the same.

Fig. 4 is a view of the operating means in side elevation and showing the parts in driving relation.

Fig. 5 is a similar view showing the disengaged position of the parts at the limit of the turning movement of the operating means.

2

Fig. 6 is an inside face view of the primary louvre-operating member showing the arrangement of its clutch disengaging cams, and

Fig. 7 is an inside face view of the operating means mounting bracket showing an end view of the supporting trunnion sleeve for the primary louvre-driving member and the means for disengaging the primary driving member from the clutch.

10 In the form shown, the improved Venetian blind comprises an operating roller 1, of suitable construction, having an internal spring, not shown, arranged in the usual manner for spring actuated curtain rollers and capable of lifting the entire blind; and a plurality of louvres 2 suspended from a tilt control bar 3 by means of the usual ladder-tapes 4. The tilt bar 3 is rotatably mounted independently of the roller 1, on a fixed axis below and parallel with the roller 20 and the assembly is disposed within a frame 5, which includes suitable louvre end-guides 6.

The usual bottom bar or rail, by which the blind is raised and lowered, is also provided and this bottom bar is suspended from the roller 1 by means of suitable tapes or straps 7, which are secured to and wound around the roller 1 whereby turning of the roller will lift or lower the bottom bar and thus raise or lower the blind. The bottom bar may also be arranged in any of several well-known ways for engagement with the louvre end-guides to provide stop means for holding the blind in the desired position of elevation.

Since this invention is particularly directed to the louvre-tilt operating means, the bottom bar of the blind is not shown herein and only one each of the ladder tapes and lifting straps is illustrated. These elements are old and well known in the art and for an illustration of a suitable arrangement of the same, which may be utilized in the practice of this invention, reference is made to my aforesaid copending application wherein a complete blind construction is shown.

45 The improved louvre tilt operating means, as herein shown, is mounted in the upper inside corner of the frame 5, at corresponding ends of the roller 1 and tilt bar 3, and both the roller and tilt bar are supported on fixed axes by the operating means. Particularly, the operating means comprises a pair of operatively meshing gear elements 8 and 9, suitably mounted on a bracket 10, and each gear element is disposed on the axis of a respective one of the roller and 50 55 the tilt bar members and is arranged to have a

driving connection therewith. Thus rotation of the roller 1 will directly cause rotation of the tilt bar 3.

As shown, the upper or primary gear element 8 of the operating means is in the form of a segment gear and the driving connection with the roller 1 is obtained through a friction clutch member 11, the hub of which is provided with a square socket 12 to receive the square shaft 13 which is fixed to and projects from the end of the roller 1, the clutch member 11 being thereby keyed to the roller 1 for rotation therewith.

The lower gear member 9, which is meshed with the primary gear 8, is arranged to receive and support the end of the tilt bar 3, the tilt bar 3 having a pair of laterally spaced pins 14 which extend into suitable sockets or openings 15 formed in the face of the gear element 9.

As shown in Fig. 3, the operating means is mounted on the bracket 10 by means of a pair of trunnion members 16 and 17 which are rigidly secured on the bracket 10 and project inwardly therefrom. The upper trunnion member 16 is in the form of a hollow sleeve press fitted into an opening in the bracket and adapted to support both the gear 8 and the clutch 11, the segment gear 8 being rotatably journaled externally on the sleeve and the clutch member 11 being provided with an axial projection or hub 18 which extends into and rotatably fits the sleeve bore. Thus the clutch member rotates within the sleeve 16 and the segment gear 8 turns on the outside of the sleeve 16, whereby the gear and clutch may rotate together or independently.

The clutch member 11 is secured in the sleeve 16 by means of a bolt 19 which is threaded into a suitably tapped socket or opening in the end of the axial projection 18, the head of the bolt 19 engaging on the inner race of a ball thrust-bearing 20 which is disposed between the head of the bolt and the outer face of the bracket 10. The outer race of the ball bearing 20 bears against the bracket 10 so that the clutch member 11 and the securing bolt 19 may turn together and be freely rotatable in the sleeve trunnion 16, while being secured against axial displacement therein.

The clutch member 11 is provided with a radial flange-like portion 21 which has a suitable friction lining 22 secured on its inner face for frictional engagement with the face of the gear segment 8. The gear segment 8, which is axially slidable on the trunnion 16, is normally urged into engagement with the clutch lining 22 by means of a coil spring 23 which surrounds the trunnion and bears axially between the opposite face of the segment gear and the outer shell of a ball thrust bearing 24. The outer shell of the bearing 24 surrounds and turns with the outer race of the bearing and the inner race of the bearing is arranged to bear against the bracket 10 so that the segment gear 8, together with the spring 23 and the shell of the bearing 24, will be freely rotatable relative to the trunnion 16 and the bracket 10.

The second gear element 9 is rotatably mounted on the trunnion or stub shaft 17 which, in turn, is rigidly secured to the bracket 10 by means of a bolt 25 which extends through a suitable opening in the bracket and is threaded into a suitably tapped opening in the end of the trunnion, the trunnion 17 having an annular shoulder engaging the inner face of the bracket member and the head of the bolt 25 bearing against the outer face of the bracket member so as to securely clamp the trunnion 17 in place. As shown, the

gear 9 is provided with a hub 26 which bears against a bushing 27 which in turn serves as a spacer to hold the gear 9 in proper aligned position with the segment gear 8.

5 The means for operating the clutch so as to disengage the tilt-bar operating mechanism from the roller 1, comprises a pair of angularly spaced pins 28 and 29 which project radially from the hollow trunnion 16 and engage a pair of cam-like portions 30 and 31 which project axially in the manner of a hub, from the body of the segment gear 8.

15 As shown in Fig. 6 these cam-like portions are diametrically opposed and are arranged to extend axially along the outer surface of the trunnion 16 toward the fixed pins 28 and 29. Each of the cam-like portions 30 and 31 is provided with a pair of opposed angularly directed finger portions 32 positioned to engage a respective pin and each 20 finger 32 is provided with an inwardly slanted cam surface arranged cause the segment gear 8 to be drawn axially on the trunnion 16, away from the friction facing 22 of the clutch member and against the action of the spring 23, whenever the gear is turned so that the fingers 32 engage the respective pins and cause them to ride on the cam surfaces.

25 This action is illustrated in Figs. 4 and 5 of the drawings in which Fig. 4 shows the finger portion 32 as it first engages the pin 28, and Fig. 5 shows the manner in which the segment gear 8 is cammed axially on the trunnion 16 by means of the slanted cam surface of the finger 32 and as it is driven to ride on the pin 28. The gear 8 is retained in cammed engagement with the pins, against the action of the spring 23, during continued rotation of the roller 1, through sliding frictional engagement of the gear with the clutch 11 since the camming effect will only be sufficient to cause the clutch to slip.

30 Thus in operation of the improved tilt-bar operating mechanism, the upper gear member 8 is normally in driving engagement with the clutch member 11 which in turn is fixed to rotate with the roller 1 and any turning movement of the roller 1 will be imparted directly to the louvre tilt bar 3 through the tilt bar gear 9, which is meshed with the upper or primary operating gear 8, the gear 8 being held in tight frictional engagement with the clutch member 11 by means of the spring 23.

35 The gear 9, however, cannot turn through one complete revolution because of overlapping engagement of the louvre slats 2 when they reach their closed position. Therefore, the gear elements 8 and 9 are preferably proportioned so that the gear element 8 need only turn through approximately 120° in order to impart a maximum turning movement of the gear element 9. The stop or camming means or pins 28 and 29 are, 40 therefore, so positioned angularly relative to each other and the cams 30 and 31 on the gear element 8 are so formed that upon turning of the roller 1 to such an extent as to cause the louvre slats 2 to turn to a fully closed overlapping position, the cams 30 and 31 will engage the stop pins 28 and 29 and cause the gear element 8 to be withdrawn or released from its spring-pressed driving connection with the clutch facing 22, whereupon the roller 1 may continue to turn without imparting any further driving or turning movement to the louvre tilt bar 3.

45 The stop pins 28 and 29 and the camming portions 30 and 31 of the segment gear 8 are so arranged that this disengaging action of the seg-

ment gear, with respect to the clutch facing, occurs at the proper point during rotation of the roller 1 in either direction. Thus, when the blind is being either raised or lowered, the louvres will turn to their overlapping or closed position and then remain stationary until the blind has been set to the desired position of elevation. Then the desired position or angular set of the louvres is obtained by merely shifting the bottom member of the blind a small distance in the opposite direction which will reverse the direction of the roller and cause the clutch to drive the operating gears to turn the louvre tilt bar 3. Since the clutch is in driving engagement with the primary gear 8 at all times, except when the louvres are turned to closed position, the driving mechanism will be immediately responsive to any movement of the bottom member of the blind, and consequently any turning of the roller 1, and any intermediate setting of the louvres is obtained by simply shifting the bottom member of the blind in the appropriate direction.

The main advantages of this invention reside in the automatic operation of the louvre tilt mechanism by the simple expedient of merely raising or lowering the blind and in the arrangement whereby the louvres can only turn to a fully closed position regardless of the extent to which the blind is raised or lowered. Thus flutter or repeated back and forth oscillation of the louvres, during manipulation of the blind, is completely obviated with the resulting elimination of rattle or clatter of the louvre slats while the blind is being raised or lowered.

Other advantages reside in the simple arrangement of the tilt operating mechanism and in the direct, quick acting, positive drive that is provided whereby the desired louvre setting is obtained with but a small change in the elevation of the blind; and in the operating means construction wherein no adjustment is ever required and wherein the mechanism is rugged, long lasting and fool proof.

Although but one specific embodiment of the invention is herein shown and described, it will be understood that many details of the construction shown may be altered or omitted without departing from the spirit of the invention as defined by the following claims.

I claim:

1. A louvred blind comprising a roller member, means to rotate said roller member, a rotatable louvre tilting member mounted independently of said roller member, operating means connected between said members and arranged to turn said tilting member upon rotation of said roller member, said operating means comprising a pair of relatively shiftable rotatable elements normally engaging each other frictionally, and means adapted to shift one of said elements out of engagement with the other at predetermined angular position of rotation of said tilting member during rotation of said roller.

2. A louvred blind comprising a roller, means to rotate said roller, a rotatable louvre tilting means mounted independently of said roller, operating means arranged to provide a driving connection between said roller and said tilting means, said operating means including a spring actuated friction clutch normally connecting a pair of relatively rotatable elements, and means adapted to release said clutch at predetermined positions of angular movement and limit the rotation of said tilting means during rotation of said roller.

3. A louvred blind comprising a roller, means to turn said roller, a shaft fixed to and extending from one end of said roller, a rotatable louvre tilting means, operating means connected to said shaft for actuation by said roller and having driving connection with said louvre tilting means to turn the same, and fixed cam means adapted to operatively disengage the connection between said operating means and said shaft during turning of said roller and at predetermined angular positions of said louvre tilting means.

4. A louvred blind comprising a roller, means to turn said roller, a shaft fixed to and extending from one end of said roller, a rotatable louvre tilting means, operating means connected to said shaft for actuation by said roller and having driving connection with said louvre tilting means to turn the same, a clutch adapted to normally connect said operating means and said shaft, and means adapted to automatically release said clutch when said louvre tilting means has turned a predetermined amount under the influence of said roller.

5. A louvred blind comprising a roller member and a rotatable louvre tilting member mounted on parallel axes, means to turn said roller member, a gear disposed on the axis of each of said members at corresponding ends thereof, said gears being in meshed driving relation with each other, one of said gears being fixedly connected to the end of its respective member and the second gear being axially shiftable relative to and having a frictional drive connection with the other member, means normally urging said second gear toward said other member, and means adapted to shift said second gear axially and release said frictional drive connection at a predetermined angular position of said tilting member during turning of said roller member.

6. A louvred blind comprising a roller member and a rotatable louvre tilting member mounted on parallel axes, means to turn said roller member, a gear disposed on the axis of each of said members at corresponding ends thereof, said gears being in meshed driving relation with each other, one of said gears being fixedly connected to the end of its respective member and the second gear being axially shiftable and having a frictional drive connection with the other member, means normally urging said second gear axially toward said other member, and means adapted to release said frictional drive connection upon a predetermined rotation of said tilting member.

7. A louvred blind comprising a roller and a rotatable louvre tilting means mounted on parallel axes, means to turn said roller, a mounting bracket disposed at one end of said roller and having a fixed sleeve projecting toward said roller along the axis thereof; a clutch member journaled in said sleeve and connected to the end of said roller for rotation therewith, an operating member journaled on said sleeve and having driving connection with said tilting means to rotate the same, said operating member being normally engaged with said clutch member, and means to release said operating member from said clutch member at a predetermined angular position of said tilting means.

8. A louvred blind comprising a roller and a rotatable louvre tilting means mounted on parallel axes, means to turn said roller, a mounting bracket disposed at one end of said roller and having a fixed sleeve projecting toward said

roller along the axis thereof; a clutch member journaled on said sleeve and connected to the end of said roller for rotation therewith, a segment gear journaled on said sleeve and slideable axially into and out of engagement with said clutch member, a stub shaft mounted on said bracket and aligned with the axis of said tilting means, a gear wheel journaled on said stub shaft and having connection with the end of said tilting means to rotate therewith, said gear wheel being in driving relation with said segment gear, means normally urging said segment gear into engagement with said clutch member, and means adapted to shift said segment gear axially away

from said clutch member at a predetermined angular position of said tilting means.
